UNITED STATES PATENT OFFICE

2,612,516

CONDENSATION CHLOROMETHYL
BENZOATES

Robert A. Heimsch and William S. Emerson,
Dayton, Ohio, assignors to Monsanto Chemical
Company, St. Louis, Mo., a corporation of Dela-
ware

No. Drawing. Application March 25, 1950,
Serial No. 151,992

7 Claims. (Cl. 260—475)

1

The present invention relates to esters of diaryl dicarboxylic acids and deals more particularly with the production of certain esters of 1,2-bis(carboxyphenyl)ethane. The invention provides an improved method for the preparation of such esters.

Esters of 1,2-bis(carboxyphenyl)ethane are highly valuable as plasticizers and as intermediates for the production of surface-active agents, water-repellants, lubricants, etc. While a number of these esters have been known for some time, their usefulness has been limited because the known methods of preparation either gave very poor yields or were based on the use of difficultly available starting materials.

Now we have found that esters of 1,2-bis(carboxyphenyl)ethane with aliphatic, saturated alcohols of from 1 to 8 carbon atoms are readily obtainable by heating an alkyl(halomethyl) benzoate in aqueous suspensions of nickel-aluminum alloys, the reaction proceeding substantially according to the scheme:

in which R is an alkyl group of from 1 to 8 carbon atoms and X is halogen. Alkyl(p-halomethyl) benzoates useful for the present purpose include methyl 4-(chloromethyl) benzoate, butyl 2-(chloromethyl) benzoate, ethyl 3-(bromo-methyl) benzoate, isoamyl 4-(iodomethyl) benzoate, 2-ethylhexyl 4-(chloromethyl) benzoate, etc. As illustrative of esters of 1,2-bis(carboxyphenyl)ethane obtainable by the present process may be mentioned 1,2-bis(4',4"-carbomethoxyphenyl)ethane, 1,2-bis(3',3"-carbobutoxyphenyl)ethane, 1,2-bis(2',2"-carbo-n-amyloxyphenyl)ethane, 1,2-bis(4',4"-carbooctyloxyphenyl)ethane, 1,2-bis(4',4"-carbo(2-ethylhexyl)oxyphenyl)ethane, 1,2-bis(4',4"-carbo-n-propoxyphenyl)ethane, etc.

Generally the self-condensation of the alkyl(halomethyl) benzoate to form the bis(carboxyphenyl)ethane compound is effected with an aqueous suspension of the nickel aluminum alloy at below the decomposition point of the halide, at say, temperatures of from 40° C. to 150° C., depending upon the nature of the individual reactants employed. Conveniently, the heating is conducted by refluxing the mixture of halide, water and the nickel alloy. Inasmuch as the

reaction appears to involve conversion of the alloy into metallic halide by dehalogenation of the alkyl(halomethyl)benzoate, the use of stoichiometric quantities of the organic halide and the nickel alloy are desirable; however, since an excess of either reactant is readily recoverable, the proportion of reactants used in the original reaction mixture is immaterial. For best yields, however, it is preferred to employ from one to two moles of the alloy per mole of the benzoate. The heating time is also comparatively unimportant, some of the bis(carboxyphenyl)alkane ester being formed as soon as the halide is contacted with the alloy. Optimum yields of the ester are obtained by conducting the heating for a time of say, one hour to twenty-four hours.

It has been found that during the reaction, some of the alkyl(halomethyl)benzoate is also converted to by-products, i. e., toluic acid and toluates. Separation of the desired dicarboxylates from the by-products is readily effected because of the wide differences in the respective boiling point and solubility characteristics.

20. In some instances, particularly when working with the higher alkyl(halomethyl)benzoates, it may be advantageous to employ an inert diluent or a polar solvent with the aqueous suspension of the nickel-aluminum alloy. As examples of such diluents or polar solvents that may be employed may be mentioned dioxane, benzene, ethanol, ether, etc.

25. The nickel-aluminum alloy found suitable for the present process may contain varying amounts of nickel alloyed with aluminum. Good results are obtainable by using the alloys described in the Raney patent, U. S. 1,628,190, and consisting of from 10% to 85% nickel and from 90% to 15% aluminum, and particularly the alloys disclosed therein which consist of approximately equal 30. quantities of nickel and aluminum. Silicon may be present. The alloy generally disclosed in U. S. Patent 1,628,190 will be hereinafter referred to 35. briefly as "Raney alloy."

40. The invention is further illustrated, but not limited by the following examples:

Example 1

45. Twelve grams of Raney alloy (from Gilman Paint and Varnish Co.) and 100 cc. of water were charged to a 500 cc. flask and the mixture was heated to a temperature of 90° C. There was then added, during a time of ten minutes and a temperature of from 90° C. to 100° C., 43 g. (0.23 mol) of methyl para-(chloromethyl)benzoate.

The resulting mixture was then refluxed for a time of two hours, cooled and filtered. The filtrate was extracted 3 times with benzene, and the reaction vessel as well as the filtering apparatus were washed with benzene in order to obtain any residue of product. The extract and the benzene washings were then combined and the benzene was removed by distillation under reduced pressure. The material which remained after separating the benzene was allowed to cool, and the crystals which formed in the cooled material were filtered off, washed with hexane and then recrystallized from methanol. The crystals thus obtained comprised substantially pure 1,2-bis(4',4''-carbomethoxyphenyl)ethane, M. P. 15 118.5° C.-119.0° C.

Example 2

This example shows the use of an inert solvent with water in the preparation of 1,2-bis(4',4''-carbomethoxyphenyl)ethane.

Forty grams of Raney alloy, 150 cc. of dioxane and 150 cc. of water were charged to a 1-liter flask and the mixture was heated to a temperature of 80° C. To the mixture there was then added 178 g. (0.965 mol) of methyl para(chloromethyl)benzoate during a time of 45 minutes and at temperatures of from 80° C. to 90° C. The resulting reaction mixture was then maintained at a temperature of from 87° C. to 91° C. for a time of 4 hours. At the end of that time 75.0 cc. of benzene was added to the reaction mixture and the whole was then cooled, with rapid stirring. The product was then filtered to remove the Raney alloy, and the filtrate was allowed to separate into an aqueous phase and an organic layer. The aqueous layer was washed with benzene, and the washings thus obtained as well as washings obtained by washing the filtered alloy with benzene were combined with the separated organic layer. Distillation of the combined organic layer and benzene washings to remove benzene and dioxane gave as residue a material from which the crude 1,2-bis(4',4''-carbomethoxyphenyl)ethane, M. P. 115-118° C., crystallized out upon cooling. Recrystallization of the crude material, employing methanol, gave the substantially pure 1,2-bis(4',4''-carbomethoxyphenyl)ethane.

Operating as in the above examples, but using ethyl, n-butyl or 2-ethylhexyl 4-(chloromethyl)benzoates instead of the methyl ester, there may be similarly obtained 1,2-bis(4',4''-carboethoxyphenyl)ethane, 1,2-bis(4',4''-carbo-n-butoxyphenyl)ethane or 1,2-bis(4',4''-carbo-(2-ethylhexyl)oxyphenyl)ethane.

We claim:

1. A process for producing a dicarboxylate having the general structure:

wherein R is an alkyl group of from 1 to 8 carbon atoms, which includes refluxing a mixture comprising Raney alloy, water and an ester having the general structure:

in which R is an alkyl group of from 1 to 8 carbon atoms, and recovering said dicarboxylate from the reaction product.

2. A process for producing a dicarboxylate having the general structure

wherein R is an alkyl radical of from 1 to 8 carbon atoms, which includes heating a mixture comprising an aqueous suspension of an alloy, containing from 10% to 85% nickel and from 90% to 15% aluminum, and an ester having the general formula

in which R is an alkyl radical of from 1 to 8 carbon atoms, and recovering said dicarboxylate from the reaction product.

3. A process for producing a dicarboxylate having the general structure

in which R is an alkyl radical of from 1 to 8 carbon atoms, which includes heating at a temperature of from 40° C. to 150° C. a mixture comprising an aqueous suspension of an alloy, containing from 10% to 85% nickel and from 90% to 15% aluminum, and an ester having the general structure

in which R is an alkyl radical of from 1 to 8 carbon atoms, and recovering said dicarboxylate from the reaction product.

4. A process for producing a condensation product which includes refluxing a mixture comprising Raney alloy, water and methyl 4-(chloromethyl)benzoate and recovering 1,2-bis(4',4''-carbomethoxyphenyl)ethane from the reaction product.

5. The process of producing a condensation product which includes refluxing a mixture comprising Raney alloy, water and ethyl 4-(chloromethyl)benzoate and recovering 1,2-bis(4',4''-carboethoxyphenyl)ethane from the reaction product.

6. The process of producing a condensation product which includes refluxing a mixture comprising Raney alloy, water, butyl 4-(chloromethyl)benzoate and recovering 1,2-bis(4',4''-carbo-butoxyphenyl)ethane from the reaction product.

7. The process of producing a condensation product which includes refluxing a mixture comprising Raney alloy, water and 2-ethylhexyl 4-(chloromethyl)benzoate and recovering 1,2-bis(4',4''-carbo-(2-ethylhexyl)oxyphenyl)ethane from the reaction product.
